UNITED STATES PATENT OFFICE.

WILLIAM J. McCARTHY, OF ROXBURY, MASSACHUSETTS, ASSIGNOR, BY MESNE ASSIGNMENTS, TO COLONIAL ROPE COMPANY, OF BOSTON, MASSACHUSETTS, A CORPORATION OF MASSACHUSETTS.

MACHINE FOR SEPARATING THE PLIES OF TWISTED ROPE.

Application filed July 31, 1923, Serial No. 654,878. Renewed June 1, 1925.

To all whom it may concern:

Be it known that I, WILLIAM J. McCARTHY, a citizen of the United States, residing at Roxbury, in the county of Suffolk and State of Massachusetts, have invented certain new and useful Improvements in Machines for Separating the Plies of Twisted Rope, of which the following is a specification.

- 10 This invention relates to machines for separating the plies of twisted rope that has been discarded, whereupon the separated plies are made into salable rope of smaller sizes.
- 15 Twisted ropes of all sizes, and especially the large hawsers from ocean liners and other large water craft, are discarded before worn out and a considerable industry could thrive on untwisting this rope and 20 re-making it. The commercial practice at present is to separate the plies by hand, a tedious and expensive operation.

The object of the present invention is to provide mechanical means for separating the 25 plies of twisted rope, that is inexpensive and simple in its operation, and can be attended by a single operator notwithstanding the fact that the large hawsers to be operated upon run to two hundred feet and more in 30 length.

To the accomplishment of this object, and such others as may hereinafter appear as will readily be understood by those skilled in the art, the invention comprises the features and 35 combinations of parts hereinafter described and then particularly pointed out in the appended claims.

The preferred form of the invention is shown in the accompanying drawing, the 40 single figure of which shows the machine in perspective, as it appears in the rope-walk or other work-room where the rope separating operation is to take place. In the drawing breaks occur in the delineation, at intervals, to indicate the great length of the larger pieces of work.

In the embodiment of the invention illustrated in the drawing a duplex machine or apparatus is shown providing means for handling to advantage both the larger and smaller sizes of rope. As illustrated, the portion of the machine for untwisting a large hawser is being used and the invention will be explained in connection with its

mode of operation on a rope of this character.

Spaced side by side down the room for the length desired, say two hundred feet, are a series of horses 2 which support a rope trough 4. The trough is blocked up on the 60 horses in any convenient manner, to maintain it in immovable position, and has open ends. The trough is quite flat, the angle between its sides being preferably about 150°, for a purpose that will appear later. 65

At one end of the trough 4 is a frame supporting two shafts 6 and 8, the journals of which are so arranged on the support that the axes of the shafts are parallel, and the trough is placed in alignment with one of 70 said shafts. The shafts 6 and 8 are provided with rope engaging hooks 10 and 12 respectively, which may be of different sizes. After the hawser has been laid in the trough one end is secured to the hook 10. In the 75 drawing the end of the hawser has been whipped and the hook then forced between the plies forward of the whipping, but any suitable or convenient mode of attaching the hawser to the hook may be employed. 80

The forward end of the hawser is un-twisted by hand for a short distance and the three separated plies, of the illustrated hawser, are secured to a draw-bar 14 which may be about seven feet long. Fastened at 85 each end, and centrally, of this bar, are swivels 16 of any usual construction. Each swivel is provided with a device suitable for holding a ply end firmly therein. As shown, these are wedge hooks 18 into which the 90 extreme end of the ply can be jammed and thus held against withdrawal. The swivels are of extreme importance, as will be understood by those skilled in the art. 95

It will be understood that as the rope un-twists, it lengthens, and in order to keep the plies taut a running draw-rope 20 is connected to the forward side of the draw-bar and extends under a guide sheave 22, on a stand 24; and then up to a drum 26, on an overhead shaft 28. The draw-rope is held taut and wound on the drum, as the hawser plies are separated, by mechanism which will now be described. Guides 30 are provided, on which the draw-bar 14 travels as it advances, thus preventing the rotating hawser from moving it out of its horizontal plane as shown in the drawing. 100 105

The mean for winding the draw-rope on its drum comprises a weight 32 the cord from which runs over a conveniently located, overhead idle sheave 34; then forwardly to a 5 ratchet carrying sheave 36, fixed on the shaft 28, about which it may be given one turn to provide sufficient friction, and then rearwardly to a drum 38, to which it is secured. So long as the drum 38 is let free to rotate 10 the weight will cause the shaft 28 to rotate and wind up the draw-rope 20 on its drum 26, thus continuously pulling the draw-bar 14 forward and keeping the untwisted plies of the hawser taut. With a hawser of the 15 length indicated the draw-bar would travel twenty or more feet before the operation is completed.

It will be observed that the shaft 28 is parallel to the draw-bar and the weight cord 20 drum 38 is fixed on a sleeve 40, loose on an overhead shaft 42, parallel to the shaft 28 but at the other or power end of the work room. The sleeve is provided at one end with the movable member 44 of a clutch of 25 any convenient construction, the fixed member 46 of which is fast on the shaft 42. The shaft 42 is continuously rotated by bevel gears 48 from the power shaft 50 which carries two pairs of fast and loose pulleys 52 and 54 from which belts run to, and drive, pulleys 56 and 58 fixed respectively on the hook carrying shafts 6 and 8 hereinbefore first referred to. Only one belt 60 for rotating the shaft 8, is illustrated.

35 The movable clutch member 44 is slid on the sleeve 40 by means of a pivoted bell-crank 62 having one arm connected thereto in the usual manner and having a spring 64 connected to its other arm for normally 40 maintaining the clutch disconnected. A cord 64 runs forward from the spring held end of the bell-crank, over conveniently located idle sheaves 66, and terminates in a depending control 67 at the operating station of the 45 machine. At this station there is a second depending control 68 which leads over an idle sheave 70 to the active end of a pivoted locking dog 72 which may be moved thereby into engagement with the teeth of a ratchet 50 74 on the ratchet sheave 36. A spring 76 is connected normally to maintain the locking dog free of the ratchet.

55 In operating the machine, after a hawser has been hooked on the hook 6 and the unwound plies attached to the swivel hooks 18 the power may be thrown in by shifting the belt 60, by a suitable belt shifter, not shown in the drawing. At this time the draw-rope is unwound from its drum 26, and the weight 60 cord is wound upon its drum 38, the clutch is disconnected and the locking dog is disengaged from its ratchet 74. The power will rotate the hook 10 in a direction to untwist the hawser in the trough and as the 65 length of the hawser increases the weight

descends keeping the separated plies taut. The swivels 16 permit the several plies to rotate individually and eventually the two outer plies ride up over the shallow sides of the trough leaving only the central ply 70 therein. The untwisting continues automatically and rapidly until the end whipping is reached when the power is shut off and the separated plies disconnected from 75 their holding devices.

In order to wind up the weight cord on its drum 38 for a succeeding operation the power is again applied and the clutch connected. The rotating drum 38 rapidly lifts the weight and when it has been completely 80 raised the clutch is disconnected. In order to hold the weight in its raised position, until the new hawser has been connected to the hook 10 and draw-bar 14, the control 68 is pulled which causes the locking dog to 85 engage its ratchet and prevent rotation of the shaft 28 under the influence of the lifted weight. On releasing the locking dog after the hawser has been connected, the weight is again ready to perform its function when 90 power is applied.

The rope untwisting hook 12, on the shaft 8, is employed for separating the plies of light rope, say from three to eight inches in diameter. No trough is required for supporting this light rope when its ends are connected, as described for the hawser, to the hook 12 and draw-bar swivels 16. In order that the draw-rope 20 may impart a direct pull to the draw-bar the guide sheave 22 may be pivotally mounted on its stand as 95 illustrated. The draw-bar guides for the light rope are not shown in the drawing but it will be understood that the operation is carried out in the manner hereinbefore described.

The nature and scope of the invention having been indicated and its preferred form having been specifically described, what is 100 claimed as new, is:—

1. A machine for separating the plies of twisted rope having, in combination, a rotary device for engaging one end of the rope, a movable device for engaging the several separated plies at the other end of the rope, means for maintaining the untwisting rope taut, and means permitting each ply to rotate individually.

2. A machine for separating the plies of twisted rope having, in combination, a draw-bar, a plurality of swivels secured to said draw-bar, means for attaching the several plies at one end of the rope to said swivels, means constantly tending to pull said draw-bar and plies forwardly, and means for rotating the rope in a direction to untwist it while it is so held and actuated.

3. A machine for separating the plies of twisted rope having, in combination, means for engaging the rope at one end, means for 110

separately engaging the several plies of the rope at its other end, means for maintaining the rope taut between said two engaging means, means for rotating the rope in a direction to separate its plies, and means permitting the plies severally to rotate in the same direction.

4. A machine for separating the plies of twisted rope having, in combination, means attached to one end of the rope for rotating the rope in a direction to untwist it, a device attached to the several plies of the rope at its other end for holding said plies separated, means for causing said device to travel forwardly in a single plane as the rope untwists, and means permitting the several plies to rotate individually as said device moves forward.

5. A machine for separating the plies of twisted rope having, in combination, means for rotating the rope in a direction to separate the plies thereof, and means for preventing the several plies from kinking as they are separated.

25 6. A machine for separating the plies of twisted rope having, in combination, means for supporting the rope throughout its length except at its ends, rotary means engaging one end of the rope having its axis 30 of rotation in alignment therewith, tension means attached to the other end of the rope by individual engagement with the several plies thereof, and means constraining said tension means to travel substantially in the 35 plane of said support as the rope is untwisted.

7. A machine for separating the plies of twisted rope having, in combination, a rope untwisting device attached to one end of the 40 rope, a draw-bar at the other end thereof having the several plies attached individually thereto, a draw-rope, a weight for maintaining said draw-rope taut, and power means for raising the weight after the rope 45 has been untwisted.

8. A machine for separating the plies of twisted rope having, in combination, a rope untwisting device attached to one end of the 50 rope, a draw-bar at the other end thereof having the several plies attached individually thereto, a draw-rope, a drum on which said draw-rope is wound, a weight for rotating said drum to maintain the draw-rope taut,

means for raising the weight after the operation on the rope is completed, and means for holding the drum from rotating until another rope is secured to said untwisting device and draw-bar.

9. A machine for separating the plies of twisted rope having, in combination, a rotary hook for engaging one end of the rope, a device for engaging separately the several plies at the other end of the rope, a weight connected and arranged to maintain the rope taut, a drum on which the weight rope is wound, a normally disconnected clutch between said drum and a power driven part of the machine, and manually operated means for connecting said clutch at the will of the operator.

10. A machine for separating the plies of a three ply twisted rope having, in combination, a shallow-trough for receiving and supporting the rope, a rotary hook in alignment with the trough for engaging one end of the rope, a draw-bar having three swivels in horizontal alignment to which the several plies at the other end of the rope are individually secured, means for maintaining the rope taut, and means for rotating the hook, whereby the swivels will also rotate as the plies separate and the two outer plies will ride up over the sides of the shallow trough leaving the centrally connected ply in the trough.

11. A machine for separating the plies of twisted rope having, in combination, rotary means adapted to be attached to one end of the rope for twisting it in a direction tending to separate its plies, and means adapted to be attached to the several plies at the other end of the rope for simultaneously nullifying the twist imparted to the separated plies by the operation of said rotary twisting means.

12. A machine for separating the plies of twisted rope having, in combination, means for rotating one end of the rope in a direction to untwist its plies, and means permitting the several plies to rotate freely during the operation of said rope rotating means, whereby each ply is in an untwisted state after the separating operation is completed.

WILLIAM J. McCARTHY.
